UNITED STATES PATENT OFFICE

SAMUEL W. HYATT, OF CONNERSVILLE, INDIANA, ASSIGNOR TO INDIANA LAMP CORPORATION, OF CONNERSVILLE, INDIANA, A CORPORATION OF INDIANA

LAMP CONSTRUCTION FOR AIRPLANES

Application filed July 26, 1929. Serial No. 381,124.

This invention relates to a lamp construction particularly for use with airplanes and to a method of mounting such a lamp upon the wing of an airplane together with control means for directing the light beam from the lamp in certain desired directions.

The principal object of the invention is to provide a lamp so positioned that the beam may be directed downward, forward or upward as desired and which may be positioned within the wing or fuselage of the plane when in flying position.

The principal feature of the invention consists in the mounting and control means for accomplishing the before-mentioned object.

Other features of the invention reside in the specific form of the lamp construction herein disclosed.

In the form of the invention herein disclosed, a lamp construction is hinged to the upper side of an airplane wing. In flying position the lamp is folded within the wing in a position to offer the least possible air resistance. The upper surface of the lamp casing then forms substantially a continuation of the curvature of the wing surface. In this position the beam of the lamp is directed downward through an aperture in the wing and is adapted to illuminate the ground or other objects beneath the plane. For use in landing, the lamp is tilted upward about its hinge until the beam is directed forward over the top of the wing. By further tilting, the lamp may be directed upward to illuminate air craft flying above the plane. The last-mentioned feature is particularly important in warfare wherein night aircraft combat may be expected in the future.

Other objects and features of the invention and the full nature thereof will be fully understood from the accompanying drawings and the following descriptions and claims:

Fig. 1 is a sectional view of an airplane wing showing a lamp in its normal flying position with the beam directed downward and showing in dotted lines the position of the lamp when the beam is directed upward.

Fig. 2 is a similar view showing the lamp

positioned for landing. Fig. 3 is a top plan view showing the form of aperture and the shape of the lamp casing. Fig. 4 is a sectional view of a preferred form of lamp construction.

A wing covering 10 is carried upon suitable frame work members not shown in the drawings. An aperture 11, preferably rectangular in shape, is provided extending vertically from the upper to the lower surface of the wing, and is surrounded by walls 12. The lower end of the aperture 11 is closed by a suitable transparent plate of glass or similar material 13. A lamp casing 14 is hinged at 15 to the framework of the wing at a point adjacent the upper edge of the aperture. The casing 14 is provided with a shoulder 16 adapted to seat upon a ledge 17 at the upper end of the walls 12 of the aperture. Pivotedly supported upon a bracket member 18 carried upon one of the walls 12 is a triple-armed bell crank 19 having one of its arms 20 extending through an opening in the adjacent wall 12. A link 21 is pivotally attached to the outer end of the bell crank arm 20 and is pivotally attached at its opposite end to a projecting member 22 fixedly carried by the lamp casing 14. Control wires 23 are attached to the remaining arms of the bell crank 19 and are trained about pulleys 24 supported within the rearward end of the wing. The wires 23 lead to suitable control levers in the cockpit or cabin of the airplane and may be manually operated by the pilot to raise or lower the lamp casing 14 to any of the positions shown in Figs. 1 and 2. By a suitable choice of the dimensions of the bell crank arm 20 and the member 22 the lamp may be positioned to direct the beam at an even greater angle to the horizontal than that shown in dotted line in Fig. 1.

In Fig. 4 are shown the details of a preferred form of lamp construction wherein the casing 14 is provided with inturned flange portions 25 adapted to contact with the outer edge of a reflector member 26. The reflector 26 carries a lamp socket 27 in turn supporting a lamp bulb 28. A suitable lens 29 is provided having a central portion 30

curved in the manner shown in Fig. 4 and having a conical portion 31 and an outer flange 32. The flange 32 is herein shown surrounded by a suitable gasket 33 in turn contacting with a portion of the reflector member 26 and with a shield member 34. The shield member 34 has an outer flange 35 contacting with the outer flange of the reflector member 26. Screws 36 extend through suitable openings in the outer flange 35 and the reflector member 26 and threadedly engage the inturned flange 25 of the casing 14. By this means the entire lamp construction is suitably clamped together. 15 A gasket 38 is provided upon the ledge 17 to form a cushion for the lamp construction when in the retracted position. Suitable electric conductors 40 supply current to the lamp from any desirable source. 20 Because of the large size of lamp bulb required for the purpose of the present invention, and because of the limited space available, it is not possible to use the ordinary type of flat head lamp lens in order to 25 provide a non-diverging beam of light. For that reason a spill light shield 37 is provided to cut off diverging rays from the outer edge of the light beam. In the present instance the shield 37 forms a part of the shield member 34 previously mentioned. 30

The invention claimed is:

1. In combination with an airplane, a lamp construction pivotally carried within a wing thereof adjacent its upper surface, 35 said wing having an aperture beneath said lamp construction through which a beam of light may be directed for downward illumination, and control means for moving said lamp construction about its pivotal mounting for forward and upward illumination. 40
2. In combination with an airplane, a lamp construction pivotally carried within a wing thereof, said wing having an aperture beneath said lamp and an aperture 45 above said lamp and said lamp being normally positioned to project its beam through said lower aperture, and control means for moving said lamp about its pivotal mounting through said upper aperture for forward and upward illumination. 50
3. In combination with an airplane, a lamp construction pivotally carried within a wing thereof, said wing having an aperture beneath said lamp and an aperture 55 above said lamp and said lamp being normally positioned to project its beam through said lower aperture and having its casing forming a closure for said upper aperture, and control means for moving said lamp 60 about its pivotal mounting through said upper aperture for forward and upward illumination. 65
4. In combination with an airplane, a lamp construction pivotally carried within a wing thereof, said wing having an aperture

beneath said lamp and an aperture above said lamp and said lamp being normally positioned to project its beam through said lower aperture and having its casing closing said upper aperture and forming substantially a continuation of the upper surface of said wing, and control means for moving said lamp about its pivotal mounting through said upper aperture for forward and upward illumination. 70

In witness whereof, I have hereunto affixed my signature.

SAMUEL W. HYATT.
